UNITED STATES PATENT OFFICE.

ROY FRANCIS ENSIGN AND ORVILLE H. ENSIGN, OF PASADENA, CALIFORNIA.

VORTEX-TYPE UPDRAFT CARBURETOR.

Application filed April 17, 1916. Serial No. 91,809.

To all whom it may concern:

Be it known that we, ROY FRANCIS ENSIGN and ORVILLE HIRAM ENSIGN, both citizens of the United States, residing at 5 Pasadena, in the county of Los Angeles and State of California, have invented a new and useful Vortex-Type Updraft Carburetor, of which the following is a specification.

Objects of this invention are; to produce 10 an updraft vortex type of carburetor; to reduce the cost, and to increase the economy, the range and the flexibility of the vortex type of carburetor, and to produce a carburetor having minimum length of air path 15 through it with minimum resistance to air flow and maximum possible power produced from a given fuel consumption.

An object of this invention is the development of the vortex type of carburetor built 20 and manufactured under the Patents Nos. 1,064,627 and 1,064,628, issued June 10, 1913, to said Orville H. Ensign, using a vortex mixing chamber for proportioning and mixing liquid fuel and air for internal 25 combustion engines. It was at first thought impossible to make a carburetor of this type in the form of an updraft carburetor, for the reason that in the vortex type of carburetor it is difficult to get a sufficient suction 30 at slow speeds at the center of the vortex to lift the liquid fuel to an elevated vortex mixing chamber.

We have discovered that by the use of 35 an air lift or an air injector this difficulty can be overcome except for extremely low speeds and that operation may be continued at such slow speeds by the use of the much greater vacuum created by the suction of the engine beyond the throttle when the 40 throttle is but slightly open.

A difficulty was discovered to exist in 45 that this greater vacuum or suction is not adapted to make a proportioned mixture, and consequently the results at slow idling speeds were not satisfactory.

We have found that the drop of pressure 50 below the atmosphere caused in producing an entrance velocity to the vortex type of carburetor from the exterior air is only a fraction of that due to the vortex, and in 55 this invention we utilize this difference as a factor in attaining the desired result.

An object of this invention is to overcome 60 the difficulty above referred to, and to provide simple and certain means for proportioning the fuel and air and effecting a

mixture of the two elements and in supplying such mixture to the engine at all speeds.

In this invention we provide a well or reservoir into which the liquid fuel is 60 caused to flow, and apply to the surface of the liquid fuel in such well, a suction created by the velocity of the inflowing air as it enters the vortex mixing chamber and apply the more violent suction produced beyond 65 the nearly closed throttle to draw liquid fuel from below such surface and to deliver the fuel thus sucked up, to the air flowing through the engine manifold beyond 70 the nearly closed throttle.

In one type of this newly-invented carburetor such suction is taken as the suction or drop of pressure caused by the air flowing into the carburetor at the periphery 75 of the vortex mixing chamber, or suction produced at any point between the center and the circumference of the vortex chamber.

An object of the invention is to automatically and invariably supply to the carburetor the predetermined proportion of fuel and air and to thoroughly mix the same and supply the mixture to the engine manifold or other conduit or the place of use and to avoid any dripping or wastage 85 of fuel.

An object of the invention is to construct a carburetor with throttle that can be easily moved even though the carburetor may be of a large size.

An object of the invention is to make provision for producing a more uniform mixture than heretofore under light loads, and in furtherance of this object we have interposed between the mixing chamber of the carburetor and the outlet therefrom a conical form of throttle valve having symmetrically-disposed ports arranged symmetrically around an axis, so that as the throttle valve is opened or closed the outflow of the mixture from the mixing chamber will be symmetrically disposed at all times around an axis of the outlet to the engine.

This feature of the invention is especially 105 applicable to the vortex chamber form of carburetor, but we do not limit its application to any specific construction of carburetor.

An object is to provide a carburetor 110 adapted to avoid interference with the vortical action at all speeds. A butterfly

throttle placed immediately above the vortex mixing chamber diminishes the vertical action when the throttle is thrown open, and this we avoid.

5 A further feature of the invention is the combination with the conical throttle valve of an auxiliary tube to carry fuel and air to the outlet.

10 We therefore regard the invention as broadly new and pioneer in that uncontrolled tangential air inlets to the vortex mixing chamber having a vertical axis provides the sole means for determining the proportion between the air and fuel in a carburetor throughout the whole range of its operations, thus avoiding the irregularity produced by wear of moving parts, as will more fully appear by the accompanying drawings and the subjoined description and 15 appended claims.

20 The accompanying drawings illustrate the invention.

25 Figure 1 is an axial sectional elevation, on line x^1 , Figs. 5 and 6, of a carburetor made in accordance with this invention and connected with an engine. The action indicated by liquid levels and direction arrows is that which takes place when the engine is running at from quarter to full power.

30 Fig. 2 is a fragmental sectional view of part of Fig. 1 indicating the action of the fuel flow when engine is idling slowly.

35 Fig. 3 is an analogous fragmental sectional view indicating the action when the engine is running at a slightly faster speed than Fig. 2.

40 Fig. 4 is a fragmental view analogous to Figs. 2 and 3 with the engine still and the carburetor quiescent.

Fig. 5 is a broken plan section on irregular line x^5 , Fig. 1.

45 Fig. 6 is a broken plan view in section on line x^6 , Fig. 1, showing the throttle partly open.

Fig. 7 is a reduced plan section on line x^7-x^8 , Fig. 1, showing the throttle fully open.

50 Fig. 8 is a reduced plan section on line x^7-x^8 , Fig. 1, showing the throttle fully closed.

Fig. 9 is an axial sectional elevation of a modified form.

Fig. 10 is a view analogous to Fig. 9 with a different form of air injector.

55 Fig. 11 is a plan section on irregular line x^{11} , Fig. 10.

Fig. 12, Sheet 1, is an enlarged fragmental view of parts of Fig. 1 to indicate in part the operation under full load.

60 The carburetor is preferably constructed in three superposed hollow sections. Each of said sections may be made in different forms, and analogous parts of the different forms shown in the drawings are distinguished from each other by exponents ap-

plied to some of the like indicating characters. The three sections are connected together and constitute respectively a constant level chamber section 1, a vortex chamber section 2 and a suction outlet and throttle chamber section 3.

65 Referring first to the generally preferred construction shown in Figs. 1 to 8, inclusive, the constant level chamber section 1 and the vortex section chamber 2 are provided with an open-ended vertical well tube 4. Said tube 4 is preferably formed as an integral tubular downward central extension of the funnel-shaped bottom of the chamber 2, which forms the top of chamber 1.

70 Said well tube 4 is externally and internally threaded at its lower end and its bore extends from below the bottom of section 1 entirely through the constant level chamber 1 to the upper side of the bottom of the vortex section 2 and said tube is provided with a gland nut 5 sectioned onto its lower end outside the section 1 for holding section 1 in position on the well tube 4 and against the said bottom of section 2. Said tube 4 is provided with liquid fuel inlets 6 that are round straight holes extending through the wall of the tube 4, and a fuel passage 7 that is controlled by an inlet needle valve 8 extending through the shell section 1 and operable from the outside to regulate the size of the orifice 7.

75 The fuel orifice 7 leads into an annular well formed between the well tube 4 and the aspirating tube 9 which extends up to a level 90 above the floor 10 of the vortex chamber 2 from a reduced bore of the well tube into which the tube 9 is screwed just above the orifice 6.

80 Said floor 10 is a thin plate supported at 105 periphery and center above the surface of the bottom 11 of the vortex chamber section 2 forming an annular air passage 12 around the tube 9 and communicating with the annular well 13 formed between the tubes 4 and 9. The outer edge of this floor 10 is provided with a suction passage formed by openings 14 to communicate through the passage 12 to the surface of liquid in the well 13 which is thus made subject to air pressure losses or drops that may occur at the openings 14. Air vent *a* provides means to apply atmospheric pressure to the liquid surface *x* in the constant level chamber.

85 The purpose of this arrangement is to supply to the surface of the liquid fuel in the well 13 a suction corresponding to that at the openings 14. Such suction will be induced and controlled by the velocity of the air flowing past the openings 14 to the vortex formed in the chamber 2.

90 An auxiliary air tube comprising intake portion 15, fuel adjuster 16 and injector 17, is inserted through the gland nut 5 and screwed into the lower portion of the tube 130.

4 and is provided with a cylindrical piston fuel adjuster portion 16 tightly fitting a smooth portion of the bore of tube 4 just below the level of the orifices 6, thus to allow longitudinal adjustment of the intake section 15 of the air injector intake portion relative to the tube 4. Said tube 15 has a reduced nozzle portion constituting the injector tube 17 projecting above the fuel adjuster 16 and terminating slightly above the quiescent level α of the liquid fuel in the constant level chamber 1. The fuel adjuster 16 is adapted to be raised and lowered by screwing and unscrewing the auxiliary air tube in the well tube, and the upper end of the fuel adjuster is adapted to be adjusted to partially close and to fully open the orifices 6, thus adjusting the orifices 6 to admit any desired portion of fuel to the exterior of the nozzle 17. Said nozzle 17 extends up into, and terminates below the top of, the aspirating tube 9, and an annular passage 18 is formed between the nozzle 17 and the aspirating tube 9, so that liquid fuel may flow from the interior of the chamber 1 through the ports 6 and the annular passage 18 into the aspirating tube 9. Fuel from the fuel chamber may thus pass to the top of the nozzle 17, and thence on, when the engine is operating.

The auxiliary tube at 15 is open to the atmosphere at its lower end and is provided with a drip cup 19 connected thereto by arms 20 and forming below the intake 21 of the auxiliary air tube a sump to receive any liquid that may drip over the top of the injector tube 17.

Means are provided to admit air tangentially to the interior of the vortex chamber that is formed inside the shell section 2, thus to produce a vortex at the top of the aspirating tube 9, when air is sucked through the outlet or throttle section 3. Any approved means may be employed for this purpose and in the form shown in Figs. 1-8 stationary tangential guide vanes 22 are arranged at the rim of the vortex chamber to direct air tangentially into the interior of the vortex chamber.

The outlet passage 23 from the vortex chamber is co-axial with the aspirating tube 9 and is located axially above such chamber and in the form shown in Figs. 1-8 is controlled by a conical ported throttle valve consisting of the outer upwardly tapering conical member 24 having upwardly tapering slots 25 therein and controlled by an inner slotted conical oscillating throttle member 26 having slots 27 and bars 28 adapted to open and close the slots 25 in the stationary throttle member 24 as the throttle member 26 is oscillated. The movable throttle member 26 is provided with a hollow stem 29 extending up through a journal box 30 into the suction member or mani-

fold 40 of the engine, and secured in place by a nut 31. Thrust washers 32, 33 are provided for holding the movable throttle member 26 in proper position relative to the stationary throttle member 24. The suction outlet and throttle chamber section 3 is provided with a slot 34 through which a handle 35 is screwed into the movable throttle member 26 for the purpose of oscillating and adjusting said member 26. Said handle is connected by any suitable means as by the throttle rod 36 for operation by the attendant.

A starting and idling fuel tube or conduit 37 is provided with a graduated intake 38 arranged below the quiescent level α of the liquid fuel in the well 13 and extending from said well to a port 39 subject to the depression beyond the throttle. This tube 37 on account of the extreme suction in the engine manifold 40 beyond the throttle when the throttle is nearly closed, provides means for giving the engine a rich mixture in starting by sucking out of well 13 the fuel which is lying quiescent in said well at the beginning of the suction produced by the starting engine; and fuel from chamber 1 will flow into well 13 due to gravity caused by the elevation of the surface of the liquid fuel above the entrance 38 and by the added force of suction produced by the air flowing, past the openings or ports, 14 into the vortex chamber and thence on to the engine. When the engine is idling slowly, gravity is the greater of these two forces, and the ratio between such suction and gravity forces gradually changes as the speed changes. When the engine speed increases until it reaches one-quarter the power of the engine the two forces are about equal and at full power the force of suction caused by air velocity at 14 may be four to eight times that of gravity.

A by-pass tube 41 is provided connected to the starting tube 37 and terminating at the bottom of the cup 19, and there being provided with a V-shaped inlet 42. This by-pass tube provides during the starting and idling actions a small amount of air to the starting tube 37 and assists in producing an atomized spray at port 39; and as the speed of the engine increases slightly above idling speed, the fuel level in the annular space 18 rises and the fuel overflows the injector 17, trickling down inside the same to the cup 19 where it is picked up by the air that is sucked through tube 41 and such fuel is carried by the air flowing through the tube 41 up to the port 39 through which it is injected or sprayed into the engine manifold 40.

As the engine speeds still higher, the vertical action at the outlet of tube 9 will cause the flow of air through the nozzle 17 by way of its cup 19 and intake 21 to be sufficiently violent to force out all the fuel drawn from the supply passage 18, driving

it in a mist out of the top of the aspirating tube 9 and violently mixing it with the incoming air which enters through the multiple passages of the tangential air inlet 43 which passages are formed between the vanes 22 and constitutes unobstructed fixed non-regulable air inlets.

The connecting conical block 44 provides a means for joining the two tubes 37 and 41 together and assists in deflecting the strong mixture flowing up through the aspirating tube 9, and directing it outwardly toward the incoming air, thus introducing it to the whirling and ascending air. A hole 45 is provided through the wall of the aspirating tube to drain fuel from the floor 10 on the shutting down of the engine.

In the form shown in Figs. 10 and 11 the vortex is induced by a single tangential air inlet horn or port 46 entering the vortex chamber 2" tangentially, thus inducing suction on the mouth of the aspirating tube 9" and the air nozzle 17"; and the aspirating tube 9" terminates at a higher plane above the quiescent level of the liquid fuel in the constant level chamber than in the form shown in Fig. 1, so as to prevent the overflow of fuel at moderate speeds into the air nozzle.

30 A handle 47 is provided to rotate the nozzle for adjusting the fuel adjuster 16' of the auxiliary air tube 15' to regulate the fuel inlets 6'. A hexagon head 48 on the cup 19 in the form shown in Fig. 1 serves the same purpose.

35 The regulating suction in annular well 13' is supplied through the tube 14' having its suction mouth 14" in the small part of the inwardly tapering inlet horn 46.

40 The liquid fuel is admitted to the carburetor from the fuel pipe 49 through the strainer 50 and through the float-controlled valve 51 which is operated by the lever 52 and the float 53 therefor to maintain a constant fuel level in chamber 1 in the usual manner.

To illustrate how the difference between the vortical and air supply pressure of the vortex chamber operates to properly measure and proportion the air and fuel, a manometer, not shown, may be applied at the point 14 and another one at the top of aspirating tube 9 to show the different pressures. When the manometer connected at 50 14 shows two inches of water pressure below atmosphere, the one at 9 will show fourteen inches below atmosphere; thus demonstrating that the centrifugal action alone of the rotating air within the mixing chamber 55 produces a gradient of pressure from the periphery of the mixing chamber to the center thereof, and the depression thus formed by centrifugal action extends from the inner end of the vanes 22 to the center of the mixing chamber. This ratio of one to seven

has been maintained throughout the designs of all sizes made. This difference is brought about by the violence of the vortex action. So in the carburetor shown in Fig. 1, the fuel used for making the motor idle easily and to make it start easily is taken from the well by the tube 37 having its inverted V intake 38 submerged below the gasoline level from $\frac{5}{8}$ to $\frac{3}{4}$ of an inch. This well is fed by the small orifice 7 controlled by the valve 8. The well is exposed to the suction of the air through a comparatively large opening formed by the numerous holes 14 at the point of maximum velocity of air flow at the inlet to the mixing chamber so that the suction of drawing fuel into the annular well 13 is that due to the velocity head of the air as it enters the vortex chamber, while the suction pulling it out of this well through tube 37 is that due to the loss of pressure through the carburetor and around the throttle which is very great at light loads, that is to say, when the throttle is nearly closed; but only such fuel can flow from this well as is drawn into it proportionally to the inflowing air.

In the form shown in Figs. 1-8 the air nozzle of the ejector is set from $\frac{1}{16}$ to $\frac{1}{8}$ of an inch above the level of the quiescent fuel, and it does not begin to feed fuel until after the vortex suction has exceeded that amount, viz, $\frac{1}{16}$ to $\frac{1}{8}$ inch. The idling speeds vortex suction may be considerably lower than $\frac{1}{8}$ of an inch, but should it be higher than that the fuel will then overflow the air tube before sufficient air velocity through this tube has been produced to carry it up into the mixing chamber. Hence, the external by-pass 41 is provided leading to the sump in the drip cup 19 on the bottom of the auxiliary air tube 15 to catch this overflow fuel and deliver it above the throttle.

The operation is as follows: To start the carburetor, close the throttle nearly tight shut, turn the motor over by hand or otherwise and all the fuel stored in the annular well 13 is immediately drawn above the throttle and there broken into a violent spray; fuel then runs into the well 13, due to both gravity and suction at 14. While the engine is operated at extreme low speeds it obtains all the fuel from the annular well drawn in there by the combined forces of gravity and by suction from 14. At a somewhat higher speed, some of it will run over the top of the injector and will be drawn by the small tube 41 to above the throttle, along with that drawn from the annular chamber or well. At still higher speeds the fuel drawn in by the vortex action along with the air to the top of the aspirating tube 9 will be discharged by the velocity of air through said aspirating tube 9 into the vortex chamber where it will be caught by

the rapid whirling action creating a very fine spray or mist, which then passes on through the throttle to the engine.

The operation is reversed when slowing down. Both of these mixtures, viz, that produced by the auxiliary air lift and injector directly into the center of the mixing chamber, and that produced by the suction at 14 into the annular chamber and delivered above the throttle are always exactly proportioned to the square of the inlet air velocity, hence, a satisfactory mixture is always produced. This has been demonstrated many times with great accuracy.

During operation at any speed, air and fuel are always drawn from the well 13 by starting or idling tube 37, and the construction and arrangement are such that the suction is sufficiently strong relative to the full inlet or supply to keep the well practically empty of fuel. The well is supplied with fuel through the adjustable restricted orifice 7, under suction due to the velocity head of the air at the ports 14. This suction drawing the fuel through the orifice 7 practically depends on the design of the vortex chamber 2 and may be $\frac{1}{4}$ to $\frac{1}{16}$ of the suction at the center of the vortex chamber; but at no time, with the motor in operation, does the pressure in the well equal atmospheric pressure. The starting or idling tube 37 has a capacity considerably less than the combined capacity of the ports 14. The ports 14 may be of any desired area as long as they are many times the area of the tube 37, so that the air drawn through tube 37 will not materially affect the pressure drop in the chamber 13 and thus increase the suction upon the orifice 7. That is to say, the fuel flow through orifice 7 is controlled by the velocity head of the air at the inner end of the tangential air inlets and by no other means. The orifices 6 during operation at any speed will supply the main portion of the fuel and this fuel will be projected by the air through the injector tube 17 into the center of the vortex mixing chamber where it is picked up by the rapidly revolving body of air in the vortex chamber, very finely broken up and carried into the conical throttle and through the same to the engine manifold. During this whole operation the relation between the air used and the amount of fuel admitted thereto through the combined inlet formed by the orifices 6 and 7, is controlled solely by the velocity head and vortical action of the whirling mass of air in the vortex mixing chamber, and by no other means.

In forms shown in Figs. 9 and 10 the tube 37 communicates with the manifold 40 through the by-pass orifices 54 beyond the throttle 55, which in these forms are shown as a butterfly valve operated by the lever 56.

The conical throttle also offers an advan-

tage over the construction shown in Figs. 9 and 10, for the reason that in a vortex the whirling air is at the lowest pressure in the center and the highest pressure near the outer wall, and if the mixture is taken out of the center, as in 9 and 10, the total loss of pressure below atmosphere of the air passing through the carburetor will be much greater than when the mixture is taken out at the rim where the pressure is highest. In the forms shown in Figs. 9 and 10 the mixture is taken out of the center of the vortex at the point of lowest pressure. The conical throttle is especially constructed to cause the mixture to be taken out at the rim of the vortex; that is to say, at the point of highest pressure.

The advantage of this is that it makes it possible to hold the engine manifold pressures more nearly to that of the atmosphere, and hence draw into the engine cylinders a greater volume of air at any given speed and with the result of a larger output of power for a given dimension of engine.

We claim:

1. A carburetor comprising proportioning means consisting of a mixing chamber of circular form; an aspirating tube extending from below and projecting upwardly into the center of the mixing chamber and adapted to supply air and fuel to said mixing chamber above the bottom thereof; means for supplying liquid fuel to the aspirating tube below the level of the bottom of the mixing chamber; unrestricted fixed non-regulable means for introducing air tangentially to the periphery of the circular mixing chamber so as to produce a violent whirl through the mass of air in the mixing chamber, thereby producing a vertical pressure-drop at the center of said chamber to cause air and fuel to be lifted into said chamber through the aspirating tube.

2. A carburetor comprising a constant-level fuel chamber open to the atmosphere; a mixing chamber located above the level of said constant-level fuel chamber; means to apply suction to the top of said mixing chamber; throttle means to control such suction; means to admit air tangentially to the periphery of the mixing chamber so as to produce by centrifugal action of said air a gradient of pressure from the periphery of said mixing chamber to the center thereof; an aspirating tube projecting upwardly into said mixing chamber at the point of greatest vertical depression; means to supply air to said aspirating tube; a well; means to supply fuel to said well from the constant level chamber; and means to supply to the surface of the fuel in the well, an air depression taken from said gradient of pressure at some point other than the center of the mixing chamber.

3. A carburetor comprising a vortex chamber, an outlet above the vortex chamber, means to supply air tangentially to the vortex chamber, a well, means to supply liquid fuel to the well, a throttle in the outlet, a conduit having an opening from the well below the liquid level thereof and discharging beyond the throttle; and an air passage communicating with the mixing chamber and the surface of the liquid in the well for controlling the flow of the liquid fuel to the well.
4. A carburetor comprising a circular mixing chamber provided with one or more tangential air inlets arranged around the periphery of said mixing chamber and provided with an outlet passage extending upward and arranged concentric around the axis of the mixing chamber, said outlet passage being controlled by a conical ported throttle valve oscillating around the axis of the mixing chamber and the outlet passage; such throttle valve; a constant level fuel chamber and fuel orifices below said mixing chamber; means for injecting fuel from said fuel orifices and chamber into the center of the mixing chamber; said means consisting of a tubular passage through the constant level chamber arranged to allow for both passage of liquid fuel and air; there being arranged within said tubular passage a vertical adjustable air tube the upper portion of which is smaller than the upper portion of said tubular passage, the lower portion fitting the same; and the lower portion being provided with a piston for adjusting fuel orifices leading into the bottom of said tubular passage.
5. A circular mixing chamber provided with tangential air inlets and provided with an axial conical ported throttle on the top side and with a constant level fuel chamber on the bottom side, said fuel chamber being provided with an air lift ejector for raising the fuel into the center of the mixing chamber, and provided also with an annular well around said ejector communicating with the air in the tangential air inlets and connected by a passage to the space above the conical throttle and provided with an adjustable fuel inlet; said ejector also provided with a fuel adjusting means.
6. A circular mixing chamber provided with tangential air inlets; and provided with an axial conical ported throttle on the top side and with a constant level fuel chamber on the bottom side; said fuel chamber being provided with an air lift ejector for raising the fuel into the center of the mixing chamber, and provided also with an annular chamber around said ejector communicating with the air in the tangential air inlets and connected by a passage to the space above the conical throttle and provided with an adjustable fuel inlet; said ejector
- also provided with a fuel adjusting means; the bottom of the air nozzle of the ejector being provided with a cup; and a smaller tube leading from the cup into said passage.
7. A carburetor comprising a fuel supply section; a vortex mixing chamber located above said fuel supply section and provided with tangential air inlets; a conical ported throttle valve above, and having the same axis as, the mixing chamber; said supply section being provided with a constant fuel supply chamber and with a suction fuel passage and an air tube; said air tube arranged projecting upwardly and terminating in said fuel passage above the liquid level of the supply chamber; there being passages leading from the liquid supply chamber into the fuel passage; an aspirating tube opening into the center of the said vortex chamber and being acted on by the suction thereof to deliver both fuel and air to the center of the vortex; said carburetor being also provided with an annular well surrounding the fuel passage and open to the air in the tangential air inlets and connected by a port through the center of the cone throttle to the space above said throttle; said annular well being supplied by a separate fuel orifice from the constant level chamber.
8. A carburetor comprising a fuel supply section; a vortex mixing chamber located above said fuel supply section and provided with tangential air inlets; a conical ported throttle valve above, and having the same axis as, the mixing chamber; said supply section being provided with a constant fuel supply chamber and with a suction fuel passage and an air tube; said air tube arranged projecting upwardly and terminating in said fuel passage above the liquid level of the supply chamber; there being passages leading from the liquid supply chamber into the fuel passage; an aspirating tube opening into the center of the said vortex chamber and being acted on by the suction thereof to deliver both fuel and air to the center of the vortex; said carburetor being also provided with an annular well surrounding the fuel passage and open to the air in the tangential air inlets and connected by a port through the center of the cone throttle to the space above said throttle; said annular well being supplied by a separate fuel orifice from the constant level chamber.
